UNITED STATES PATENT OFFICE.

FRED E. HAUSE, OF ASBURY PARK, AND JOHN ZOLLINGER, OF OAKHURST, NEW JERSEY, ASSIGNORS OF ONE-HALF TO NEW JERSEY SAND AND GRAVEL COMPANY, OF SPRING LAKE, NEW JERSEY, A CORPORATION OF NEW JERSEY.

CENTRIFUGAL PUMP.

Application filed May 28, 1928. Serial No. 281,034.

This invention relates to centrifugal pumps.

One object of this invention is to provide a device of the character described which is of 5 improved construction to particularly resist the wear that is caused by sand, gravel, or other foreign substances that might enter the pump.

Another object of this invention is to provide a device of the nature set forth wherein an improved sectional construction permits rapid and inexpensive replacement of worn parts in the field.

A further object of this invention is the 15 provision of a device of the type mentioned, comprising an improved thrust bearing that can be readjusted with facility and accuracy, and which is simple and foolproof in construction, and applicable, nevertheless, to machines of varying kinds.

Still another object of this invention is to furnish a device of the species alluded to in which an improved water circulatory system safeguards the bearing of the rotor against 25 wear by grit and the like.

Still a further object of the invention is to produce a device of the class mentioned having an improved wear resisting bearing and lubricating system therefor.

30 Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawing, wherein like parts are designated by the same reference 40 characters throughout the several views.

In the drawing:

Figure 1 is a vertical section of an embodiment of the invention.

Fig. 2 is a sectional view taken on line 2—2 45 of Fig. 1.

Fig. 3 is an enlarged vertical section with parts broken away showing a thrust bearing made according to our invention.

Fig. 4 is a top view of the thrust bearing 50 shown in Fig. 3, but removed from the races.

Fig. 5 is a vertical sectional view taken on line 5—5 of Fig. 4.

Figs. 6 and 7 are respectively side and end views of a detail of invention.

The advantages of the invention as here 55 outlined are best realized when all of its features and instrumentalities are combined in one and the same structure, but, useful devices may be produced embodying less than the whole. 60

It will be obvious to those skilled in the art to which the invention appertains, that the same may be incorporated in several different constructions. The accompanying drawing, therefore, is submitted merely as 65 showing the preferred exemplification of the invention.

Generally described, the invention provides a sand and gravel pump which cuts down to a minimum the replacement cost of 70 parts, thus making the mining of sand, gravel, or other wearing material more profitable. The pump is of the centrifugal type, and since the sand and gravel passing through the pump is of a highly abrasive 75 character, the pump is made in sections to permit the renewal of such parts as receive the most wear and abuse. These sections are preferably made of a high grade steel, and enclosing the same is a pump housing that 80 may be made of cast iron, or other inexpensive material. The said housing is split above the center to provide an opening through which the sections may be replaced, but without disturbing the bearing. To reduce the machining that might be necessary as between these sections and the housing, 85 contact is provided only at predetermined spaced points. Bolts to secure the sections to the housing are reduced to a minimum 90 through interlocking coaction between the sections, whereby the latter are thus anchored in place.

To prevent grit from depositing in the bearing, and also at the adjacent hub and 95 housing plate of the pump, with the consequent cutting loose and destruction of these parts due to the churning of the abrasive material, guide means properly direct a stream of water to flush these several parts. 100

The thrust bearing serves to keep the impeller in the central plane of the pump, the side clearance being evenly distributed to prevent excessive wear on the suction side 5 of the impeller. This thrust bearing includes a pair of split resilient sleeves, and a pair of clamps to secure the same to the impeller shaft. Keys engaging the sleeves and clamps retain the same in proper clamping 10 co-operation. Through the use of taper pins, coacting between the clamps and the keys, the sleeves are set in desired adjusted position.

Referring in detail to the drawings, 10 15 denotes a device embodying the invention. The same comprises a centrifugal pump 11, adapted for use in mining sand, gravel, and other hard materials. A thrust bearing 12 20 co-operates with the pump 11, and is mounted therewith upon a base 13.

The pump 11 includes a housing 14 having an inlet connection 15. The latter is formed as an integral part of the suction 25 disc 16. The opposite wall of the pump consists of the hub disc 17. Interconnecting these discs is a peripheral casing member 18 having a discharge opening 19.

In the upper portion of the housing is an 30 opening 20 of relatively considerable size, for a purpose hereinafter described. Closing the said opening is a cover 21, which provides a continuous uniform structure with the other parts of the housing. This cover 35 is secured to the housing by any suitable means, as for example, bolts 22.

Positioned within the housing is an impeller 23 mounted on a shaft 24. The latter is journaled in a bearing 25 secured to a hub 26 of the disc 17. The said impeller is preferably 40 made of manganese steel to resist the wear of abrasive material, such as sand or gravel.

The housing is made of cast iron, or other 45 similar inexpensive material, and is protected interiorly against the wearing action of the abrasive material by steel liners. These may be made of a carbon or alloy steel, and are constructed in sections to be readily 50 replaceable, preferably through the opening 20, on removing the cover 21.

The sections aforesaid comprise disc liners 55 27, 28 extending along the suction and hub discs respectively. The liners 27, 28 are preferably made of a carbon steel. Held in place by disc liner 27 is a suction sleeve 29, which communicates between the inlet 15 and the interior of the impeller 23. This sleeve is of 60 angle form in cross section, and includes a flange 30 received in a corresponding recess 65 in the suction disc 16, while the body of this sleeve projects through openings 31 in its co-acting liner into the impeller 23. Rigidly securing the liners 27, 28 to the corresponding portions of the pump housing are bolts

32. A predetermined clearance is observed between the impeller and the said liners.

Extending around the disc liners 27, 28 are annular side members 33. These are spaced more closely to one another than the liners 70 referred to so as to partially overlie the impeller. They are preferably made of manganese steel. Ring flanges 34 extend laterally from the said liners into engagement between the aforesaid liners and the main 75 casing. To secure the members 33 to the said casing, bolts 35 may be provided, which may likewise engage the side walls 16, 17 of casing with circular portion 18 thereof.

Segmental liners 36 to 41 extend along the 80 internal surface of the member 18, and provide the track in which the heavy solid particles move with a high velocity. Due to the high degree of wear on these liners, they are made of manganese steel. To require the minimum amount of machining, the liners 36 to 41 have three point contact with the pump casing, namely, at 42, 43 and 44. The liners 38, 39 and 40 rest on the annular side liners 33. 85

To permit any of the segmental liners to be rapidly replaced in the field, they are arranged to be free of any bolts to fasten the same to the pump casing, and to be, nevertheless, retained reliably in position. In aid 90 of this object, the said liners may have interlocking engagement with each other, as, for instance, at 45. The interlock here provided consists of a projecting portion 46 of liner 41 engaging a similar portion 47, of liner 36, with the formation, nevertheless, of a uniform interior surface. The upper liner 39 is clamped in place by the cover 21. 95

In assembling the pump, sleeve liner 36 100 is first placed into the discharge opening 19, and then the liner 41 is dropped into place through the opening 20 to engage the first mentioned liner. Thereafter the remaining segmental liners are placed in position to 105 complete the circle. It will be appreciated that by making the opening 22 as large as possible, the use of a relatively long lining segment is possible. Nevertheless, the said opening is above the center of the pump so 110 that the bearing of the pump is not disturbed. Finally, the cover of the pump is applied and made tight with a rubber gasket 48. 115

To prevent accumulation of sand or grit 120 in the bearing or hub, the shaft 24 is bored centrally at 50, the end of the bore being plugged at 51. A stream of water under pressure from a forced feed connection 53 enters the hollow shaft through radially drilled holes 52 at the outer end of the hub and shaft, there being other radial holes, hereinafter described, to allow the water to 125 discharge from the shaft in the form of a spray at the inner end of the baffle plate. The bearing 25 is thus lubricated by water, this 130

being facilitated particularly by novel bearing construction now to be described.

The bearing 25 comprises a cutless bearing member 54. This is made preferably of 5 rubber and has been proved highly efficient, eliminating the need for oil lubrication. The bearing also includes packing 55 and a gland 56 therefor.

Within the hub 26 is a baffle plate 57, which 10 is of frusto-conical form, and in alinement with the said shaft. The said baffle plate is preferably made of manganese steel. The smaller end of the baffle plate is in proximity to the bearing, while the larger end there- 15 of is flanged outward at 58 to engage within a recess in which the flange 58 is locked by the disc 28.

The interior of the baffle plate is in communication with the clearance space between 20 the impeller and the adjacent stationary portions of the pump. The hub 60 of the impeller, which engages the shaft 24, may also extend into the baffle plate, and this forms a conical annular space 61 for a purpose now 25 to be described.

A plurality of radial openings 62, preferably three in number, communicate with the bore 50 to discharge the water into the baffle plate at the smaller end thereof. This 30 water, due to the rotation of the shaft, provides a spray, which effectively flushes the spaces between the impeller and the disc 28. Likewise, sand and other solid material are prevented from lodging in the hub 26 and 35 the bearing. Accordingly, the harmful effects heretofore obtained, causing, for example, bolts 63 to be sheared by the abrasive material, due to the churning thereof, with the consequent destruction of the hub and 40 bearing are eliminated. This water also prevents the pump from losing its prime. It will be apparent that water may also be let into the pump at the suction side.

To retain the impeller in the true central 45 plane of the pump and counteract the tendency for the impeller to move toward the right owing to the effect of suction thereon, the thrust bearing 12 is employed. This comprises a support 64 which forms an oil 50 box surmounted by a cover 65. Extending between the pump and the frame 64 is a stabilizer 66. By this improved thrust bearing, no collars need be formed on the shaft.

The thrust bearing includes a pair of races 55 67 in the end wall 68 of the oil box. Adjacent to these races, are felt washers 69, retained by washers 70.

Taking around the shaft are a pair of 60 clamping sleeves 71. These comprise the strong rigid collar portions 82, that seat within the inner rings 73 of the races. The said collars are flanged at 74 to abut laterally against the rings 73. The flanges 74 are recessed at 75 for a purpose hereinafter set 65 forth. The said sleeves 71 include also a com-

paratively thin walled sleeve portion 76, which is severed from the portion 72 except at 77. This sleeve portion 76 is split longitudinally at 76^a. This renders the portion 76 adapted to be sprung together for engaging 70 the shaft 24 it being understood that the sleeve 71 is bored to receive the shaft with a slight clearance. The member 71 may, however, be made with the portions 72 and 76 separate 75 from one another.

Clamps 78 have individual co-operation with the sleeves 71, and serve to secure the latter to the shaft. Each clamp 78 comprises a plurality of separate members 79 which have side and end re-enforcing flanges 80, 81, respectively. With a flange 81 positioned against the flange 74 of the sleeve, the side flanges 80 are bolted together at 82.

To retain the clamp 78 in proper angular relation to its sleeve 71, the clamp is formed 85 with a plurality of ridges 83, which are recessed longitudinally at 84, to aline with the openings 75 in the flange 74. On placing a key 85 into these alined openings, any relative turning is prevented, so that clamp 78 90 will always act in a direction to flex the sleeve portion 76.

Preferably, the keys 85 extend into engagement with the aforesaid parts at both ends 95 of the thrust bearing. These keys are utilized as a means for initially driving the sleeves 71 apart and into snug engagement with the races 67. Accordingly alined holes 86 are made in the side walls of the ridges 83, and holes 87 in the keys 85. Taper pins 88 are 100 then forced into the holes 86 and 87, these being initially out of alinement so as to cause the keys 85 to drive the clamps 78 and in turn the sleeves 71 apart as aforesaid. These keys 105 can be replaced at any time by others, having holes differently drilled.

It is thus seen that we have provided a device which fulfills the several objects of the invention and is well adapted to meet the conditions of practical use.

We claim

1. A device of the character set forth, including a centrifugal pump comprising a housing, an impeller therein, the housing including a cover wholly at one side of the axis 115 of the pump, and sectional replaceable liners in the housing to protect the same, said liners being removable from the housing on removing said cover, said liners including separate peripheral and side liners, said peripheral liners being replaceable through the opening provided on removing said cover.

2. A device of the character set forth, including a centrifugal pump, the same comprising a housing, an impeller therein, discs concentric with the impeller, said discs being between the sides of the impeller and the side walls of the housing, side liners extending along the side walls of the housing, and around the peripheries of the discs, and split 125 130

shell liners extending along the inner circumference of the housing and around the side liners, said housing having an opening to one side of the axis thereof for replacement of the shell liners, and a cover for said opening.

3. A device of the character set forth, including a centrifugal pump comprising a housing, an impeller therein, a shaft for the impeller, a hub for the shaft, a baffle between the hub and the impeller to protect the former, said shaft being hollow and having radial holes therein at the hub and at a portion of the shaft on that side of the baffle nearest to the impeller, said holes communicating with the hollow in the shaft, and means to supply water through the hub to the hollow shaft, the water entering and being discharged through said radial holes in the form of a spray along the baffle.

20 4. A centrifugal pump, including a housing having an outlet and an opening remote therefrom, said opening being wholly on one side of the axis of the housing, a cover for said opening, an impeller in the housing, and peripheral sectional liners in the housing adapted to be inserted through said opening, one of said liners extending into said outlet, and being removable therethrough, the last mentioned liner having interlocking engagement with an adjacent liner to be retained in the housing.

5. A centrifugal pump including a housing, a shaft through the housing, a hub for the shaft, an impeller in the housing on said shaft, a conical baffle in the hub and through which the shaft passes, the large end of the baffle being in proximity to the impeller and in close contact with the wall of the housing, the other end of the baffle fitting comparatively closely about the shaft, the shaft having a hole in the baffle to discharge a liquid along the concave wall thereof to prevent infiltration of grit into the hub.

In testimony whereof we affix our signatures.

FRED. E. HAUSE.
JOHN ZOLLINGER.
